GRAB UNIT

Robert G. Le Tourneau, Longview, Tex., assignor
to R. G. Le Tourneau, Inc., Stockton, Calif., a
corporation

Application April 12, 1947, Serial No. 741,048

5 Claims. (Cl. 294—107)

1

This invention has for an object the provision of a novel grab unit or grapple adapted for use with a hoist to engage and lift material. While designed for use with material, such as hay, logs, sugar cane, or the like, the grab unit obviously may be put to other uses to which it may be adaptable.

Another object of the invention is to provide a grab unit wherein the grab elements are actuated by a cable system wholly independent of the hoist so that the grab unit may be opened or closed at any elevation without regard to operation of the hoist.

A further object of the invention is to provide a grab unit, as in the preceding paragraph, wherein the actuating cable system is powered by a reversible electric motor unit mounted directly on, and traveling with, the hoist suspended frame of the grab unit.

An additional object contemplates the embodiment, in the grab unit, of a novel sheave assembly to which the actuating cable system is connected.

It is also an object to incorporate a novel rotary shaft and mounting arrangement for the grab element; the shafts being hollow box beams, and the grab elements projecting from angle brackets symmetrically engaging over, and secured to, portions of said shafts.

A further object of the invention is to provide a practical but simple and relatively inexpensive grab unit, and one which will be exceedingly effective for the purpose for which it is designed.

These objects are accomplished by means of such structure and relative arrangement of parts as will fully appear by a perusal of the following specification and claims.

In the drawings:

Fig. 1 is an end view of the grab unit, closed.

Fig. 2 is a plan view of the grab unit, open.

Fig. 3 is a cross section on line 3—3 of Fig. 2 showing the grab unit open.

Fig. 4 is a fragmentary sectional elevation illustrating the reeving of the grab unit closing cables.

Fig. 5 is an enlarged fragmentary cross section showing the journaling of one end of one cross shaft in connection with the corresponding end beam.

Referring now more particularly to the characters of reference on the drawings, the grab unit comprises a rigid horizontal frame, indicated generally at 1, which frame comprises, in parallel relation, a pair of spaced end beams 2 connected together by a central cross beam 3.

At each side the frame supports a rotary cross

2

shaft 4 which is of hollow box beam type, preferably square in cross section; said rotary cross shafts being journaled, at the ends, in connection with corresponding end portions of the beams 2, as follows:

Each rotary cross shaft 4 is formed, at opposite ends, with an axial boss 5 which engages in a bearing 6 carried in a bracket block 7 suspended, in fixed relation, from the adjacent end portion of the corresponding end beam 2. A suitable seal 8 prevents access of dust and foreign material into each bearing 6.

The cross shafts 4 are each fitted, at longitudinally spaced points thereon, with a depending arcuate grab hook 9 which faces inwardly; the corresponding grab hooks 9 on the cross shafts 4 at opposite ends of the device being in cooperative alinement. The grab hooks 9 are affixed to the corresponding rotary cross shaft 4 by means of an angle bracket 10 which symmetrically engages over the cross shaft 4 from one corner thereof. The angle brackets 10 are secured to the cross shafts 4 in any suitable manner.

By reason of the above arrangement the grab hooks 9 may be secured at any selected points along the cross shafts 4, and such hooks may be replaced, if broken or worn, without removing the corresponding cross shaft.

The grab unit is adapted to be suspended from a hoist hook 11 by means of a rigid upstanding suspension plate 12 affixed to the cross beam 3 centrally of its ends in facing relation to the end beams 2. At its upper end the suspension plate 12 includes an eye 13, through which the hoist hook 11 is adapted to engage. The hoist hook 11 is part of any suitable hoist system, not otherwise shown.

The grab hook assemblies 9, as formed in connection with the rotary cross shafts 4, are adapted to be power actuated between the closed position of Fig. 1 and the open position of Figs. 2 and 3, by means of the following arrangement:

A reversible electric motor unit, indicated at 14, is mounted on the vertical suspension plate on one side thereof, and includes a drive shaft 15 projecting through suspension plate 12 to the other side thereof horizontally and parallel to the central cross beam 3. On the side of the suspension plate 12 opposite said electric motor unit, the drive shaft 15 is fitted with a cable drum 16. The reversible electric motor unit includes a reduction gear train, and an automatic brake, the latter normally being set, but releasing of itself when the electric motor is energized in either direction of rotation.

The rotary cross shafts 4 are each fitted, in alignment with the cable drum 16, with a pair of half sheaves, indicated at 17 and 18, respectively; the sheaves of each pair being secured to the corresponding rotary cross shaft 4 180° apart and slightly offset axially relative to each other.

A pair of pull cables 19 lead from the cable drum 16 in the same direction, and thence separate and extend about the half sheaves 17 from the bottom thereof. The free ends of the pull cables 19, at their lower ends, lead off the half sheaves 17 and pass through holes 20 in the adjacent portions of the half sheaves 18, whence said ends of the cables are dead-ended to the latter.

The upper ends of the cables 19, after passing about the cable drum 16, are locked or dead-ended in chordal bores 21 in said cable drum. Upon rotation of the cable drum 16, by the reversible electric motor unit 14 in a direction to wind the cables 19 onto such drum, the half sheaves 17 are rotated in a direction to cause powered closing of the grab hooks 9.

To open the grab hook assemblies on the rotary cross shafts 4, there is provided another pair of pull cables, indicated at 22. At their upper ends the pull cables 22 are secured to the cable drum 16 in the same manner as described in connection with the cables 19, and thence such pull cables 22 lead off the cable drum 16 in the same direction, but opposite to the lead-off direction of the cables 19.

From the drum 16 the cables 22 lead in opposite directions to, and extend about, the half sheaves 18 from the top of the latter.

At their lower free ends the pull cables 22 run off the half sheaves 18 and pass through holes 23 in the adjacent portions of the half sheaves 17, whence said ends of the cables 22 are dead-ended.

By running the cable drum 16, by the reversible electric motor 14, in a direction to pay the cables 19 off the drum 16, and to wind the cables 22 onto said drum, the grab hooks 9 are power actuated to open position.

The use of the split or half sheave arrangement for coupling the cables 19 and 22 in rotative relation to the cross shaft 4 provides a very simple and yet efficient means of accomplishing the desired result. Additionally, this half sheave arrangement, taken with the rectangular box beam shafts 4 and grab hook attaching angle brackets 10, provides a most practical and simple means of initial manufacture, and the resulting assembly is nevertheless quite strong and rugged.

As the actuating cable system is wholly independent of the hoist, the grab hooks 9 can be opened or closed by the reversible electric motor unit 14 in any position of elevation of the grab unit; this being a feature not present in certain grabs or grapples heretofore known, wherein actuation of the grab hooks was inter-dependent upon operation of the hoist.

The present grab unit, being power actuated both in an opening and closing direction, can forcefully and positively engage a load, and yet quickly and easily release the same when desired.

For the purpose of clarity, the electric supply and control circuit for the reversible electric motor unit 14 is omitted, but may be of any conventional type.

From the foregoing description it will be readily seen that there has been produced such a

device as substantially fulfills the objects of the invention as forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. A grab hook unit comprising a pair of spaced parallel end beams, a cross beam rigidly connected to said end beams substantially midway between their ends, a flat vertically upstanding suspension plate rigidly fixed to the cross beam substantially midway of its length, the flat sides of the plate being disposed in facing relation to the end beams, a cross shaft extending between adjacent ends of the end beams and journaled thereon, grab hooks fixed on the cross shafts, a reversible electric motor fixed to one face of the vertical plate with its driven shaft projecting through the plate, a cable drum on said motor shaft and disposed adjacent the opposite side of the plate, a sheave unit mounted on each cross shaft in substantial alignment with the drum, and a cable system connected between the drum and sheaves and effective to rotate the cross shafts upon operation of the motor.

2. In a grab unit, a frame comprising parallel end beams and a centrally disposed cross beam connecting the end beams, a rotary shaft journaled adjacent each side of the frame between the adjacent ends of the end beams, grab elements depending from each shaft, an upstanding suspension plate on the cross beam, a reversible electric motor unit mounted on one side of the plate, a cable system mounted on the opposite side of the plate, such cable system being connected in driven relation with the motor and in driving relation with the shafts.

3. In a grab unit, a frame comprising parallel end beams and a centrally disposed cross beam connecting the end beams, a rotary shaft journaled adjacent each side of the frame between the adjacent ends of the end beams, grab elements depending from each shaft, an upstanding suspension plate on the cross beam, a reversible electric motor unit mounted on one side of the plate, a cable drum mounted on the opposite side of the plate and connected in driven relation with the motor, and cables connected with the drum and shafts and operative to reversibly and oppositely rotate the shafts.

4. In a grab unit, a frame comprising parallel end beams and a centrally disposed cross beam connecting the end beams, a rotary shaft journaled adjacent each side of the frame between the adjacent ends of the end beams, grab elements depending from each shaft, an upstanding suspension plate on the cross beam, a reversible electric motor unit mounted on one side of the plate, a cable drum mounted on the opposite side of the plate and connected in driven relation with the motor, a pair of sheaves mounted on each shaft in alignment with the cable drum, a first pair of pull cables secured to and leading in the same direction off the drum and thence diverging relative to each other, one cable of said first pair of cables extending to and under one of the sheaves on one shaft, the outer end of the cable being fixed relative to said sheave, the other cable of said first pair of cables extending to and under one of the sheaves on the other shaft, the outer

end of such cable being fixed relative to such sheave, a second pair of pull cables secured to the drum and leading therefrom in a direction opposite to that taken by the first pair of cables and then diverging relative to each other, one cable of said second pair of cables extending to and over the other sheave on said one shaft, the outer end of such cable being fixed relative to such sheave, the other cable of said second pair of cables then extending to and over the other sheave on said other shaft, the outer end of such cable being fixed relative to such sheave.

5. In a grab unit, a frame comprising parallel end beams and a centrally disposed cross beam connecting the end beams, a rotary shaft journaled adjacent each side of the frame between the adjacent ends of the end beams, grab elements depending from each shaft, an upstanding suspension plate on the cross beam, a reversible electric motor unit mounted on one side of the plate, a cable drum mounted on the opposite side of the plate and connected in driven relation with the motor, a pair of half sheaves mounted on each shaft in alignment with the cable drum, each half sheave of a pair being attached to the shaft in circumferential and axial offset relation with respect to the adjacent half sheave of such pair, a first pair of pull cables secured to the drum and leading in the same direction off the drum and then diverging relative to each other, one cable of said first pair of cables extending to and under one of the half sheaves

on one shaft and having its outer end dead-ended on the adjacent half sheave, the other cable of said first pair of cables extending to and under one of the half sheaves on the other shaft and having its outer end dead-ended on the adjacent half sheave, a second pair of pull cables fixed to the drum and leading together therefrom in a direction opposite that taken by the first pair of cables and then diverging, one cable of said second pair of cables then extending to and over the other half sheave on said one shaft and having its outer end dead-ended on the adjacent half sheave, the other cable of said second pair of cables extending to and over the other half sheave on said other shaft and having its outer end dead-ended on the adjacent sheave.
